DESIGN FOR A GLOVE

Jacob Neivert, New York, N. Y.

Application June 9, 1937, Serial No. 69,747

Term of patent 3½ years

To all whom it may concern:

Be it known that I, Jacob Neivert, a citizen of the United States of America, residing in Manhattan, county of New York, and State of New York, have invented a new, original, and ornamental Design for a Glove, of which the following is a specification, reference being had to the accompanying drawing, forming part thereof, wherein,

The characteristic feature of my design resides in the combination on a one piece glove of a contrasting back midsection and overlapping flaps over the contrasting seam portions of the glove as shown and a relatively arranged center flap.

I claim:

The ornamental design for a glove, substantially as shown, and described.

JACOB NEIVERT.
